UNITED STATES PATENT OFFICE

2,496,375

CIGARETTE MAKING DEVICE

Harry W. Carter, North East, Pa.

Application October 12, 1945, Serial No. 621,947

1 Claim. (Cl. 131—75)

1

This invention relates to a cigarette making device and more particularly to a device for forming an individual tube of cigarette paper and filling same with tobacco.

An object of this invention is to provide an improved cigarette making device having a tubular compartment for holding a charge of tobacco, the tubular compartment being adapted for insertion in a cigarette paper tube, and having plunger means for simultaneously ejecting the tobacco and paper from the tubular compartment.

Another object of this invention is to provide a cigarette making device comprising a metallic scoop to gather up a charge of tobacco wherein the scoop can be folded to form a tubular mold, the mold being adapted to be encircled with cigarette paper formed into a paper tube, and having means to withdraw the mold leaving the tobacco in the cigarette paper tube.

It is a further object of this invention to provide an improved device for making cigarettes by hand having a tubular mold for receiving a charge of tobacco within the mold and a cigarette paper tube around the mold, and having a plunger for ejecting the tobacco and a cylinder for ejecting the cigarette paper tube simultaneously to form a complete cigarette.

Other objects of this invention will appear from the following specification and claims and from the accompanying drawing illustrating the invention, wherein:

Figure 1 is a front elevational view of the cigarette making device showing the cigarette paper around the mold;

Figure 2 is a rear elevational view also showing the cigarette paper around the mold;

Figure 3 is a rear elevational view showing the mold in withdrawn position with the completed cigarette at the left;

Figure 4 is a sectional view showing the interior construction of the plunger and cylinder;

Figure 5 is an enlarged fragmentary sectional view showing the construction of the interconnection between the mold, the plunger and the cylinder;

Figure 6 is a sectional view taken on line 6—6 of Figure 1; and

Figure 7 is a sectional view taken on line 7—7 of Figure 1 and showing the hinged construction of the mold.

Referring to the drawing, the cylinder 1 having flared ends is closed off at the right end by a cap 2 and has a ring 3 fastened to the left end

2

to cover the edge of the cylinder. The cylinder 1 is provided with a longitudinal slot 4 intermediate the ends of the cylinder, as shown in Figure 2. Surrounding the cylinder and slideable along its length between cap 2 and ring 3 is a ring 5 formed with a pair of outwardly extending tabs 6 and an inwardly extending tab 7, struck out of the material. The inwardly extending tab 7 extends into the slot 4 to prevent the ring 5 from having rotary movement relative the cylinder 1 and yet permit relative longitudinal movement therewith.

The interior of the cylinder has fixed therein along its axis a plunger 8 having a disc 9 wedged into fixed position at the right end of the cylinder and having a head 10 fixed to the left end of the plunger 8 and spaced from the wall of the cylinder 1. Slidable within the cylinder 1 is a tubular mold 11 being split longitudinally for the major portion of its length to form two substantially semi-circular sections hinged together at 12. One of the sections, denoted by the numeral 13, is integral with the tube 11, and the other section is denoted by numeral 14. The tubular mold 11 is insertable in the cylinder 1, as can be seen in Figure 4 and by dotted lines in Figure 2. When sections 13 and 14 are swung open, in the direction of the dotted arrows of Figure 7, they form a scoop which can be inserted in a tobacco pouch for scooping out a charge of tobacco, and when closed the sections 13 and 14 form a combination of tube 11 and are insertable as a unit in the cylinder 1, as shown in Figure 3. The right end of tube 11 has an opening 15, in alignment with the slot 4, and the tab 7 projects through opening 15 so that when the ring 5 slides over the cylinder 1, it carries the tubular mold 11 including the sections 13 and 14. Thus in Figure 2, the ring 5 and mold 11 are at their extreme left position and in Figure 3, these parts are in their extreme right position.

The cigarette making device of this invention is preferably made of metal but may also be constructed of any rigid material.

In operation, the ring 5 is pushed to its extreme forward position, as shown in Figure 1, and the sections 13 and 14 are swung open to form a scoop. The scoop is inserted into a can of tobacco or a tobacco pouch to remove a charge of tobacco which is spread evenly on the scoop. The sections 13 and 14 are then closed forming a tubular mold. Then a sheet of cigarette paper 16 is wrapped around the tubular mold and the

edges moistened and stuck together to form a tube of paper around the mold. At this point, the charge of tobacco is in the mold and the paper tube is around the outside of the mold. Then with the forefinger and second finger pressing against the forward side of the tabs 6 and the thumb pressing on cap 2, the fingers and thumb are pressed together causing the ring 5 to move backwardly carrying the mold 11, with sections 13 and 14 within the cylinder 1 while the head 10 on plunger 8 prevents the tobacco from moving back. At the same time, the ring 3 on cylinder 1 prevents the paper tube 16 from moving back, so that when the ring 5 reaches its extreme backward position, as shown in Figure 3, the tobacco is left in the paper tube and the cigarette is formed. In other words, the mold is withdrawn while means are provided to hold the tobacco and paper in the original position. If desired, the ring 5 can be held stationary while the cylinder 1 is pushed forward. In this case the plunger 8 will force the tobacco out of the mold 11 while the cylinder forces the paper tube off of the mold 11, thus completing the cigarette.

While a certain specific embodiment of this invention has been shown, it will be understood that various modifications may be made within the spirit of the invention. Therefore no limitations on the invention are intended other than are imposed by the scope of the appended claim.

I claim:

A cigarette-making device comprising a cylinder, a plunger fixed to and within said cylinder, a ring slideable on said cylinder, said ring having a pair of outwardly-extending tabs struck out of the material thereof, said tabs providing finger grips to facilitate sliding movement of said ring over said cylinder, a longitudinal slot in said cylinder, a lug on said ring, said lug being

struck out of the material of said ring and projecting inwardly through said slot, a tubular mold telescopically connected to said cylinder, said mold being split along part of its length to form two semi-circular sections, a hinge for connecting said sections, said hinge being formed internally of said mold, whereby when said sections are in open position they are adapted to form a scoop for scooping a charge of tobacco from a source of tobacco, and when in closed position, they are adapted to receive a cigarette paper tube therearound, said plunger having a notched portion for clearing said hinge, said mold having an opening in the unsplit portion thereof, said lug extending through said opening, whereby when the mold is filled with tobacco and a cigarette paper tube is fitted over said mold, movement of said ring along said cylinder causes said mold to be withdrawn to a position within the cylinder while said cylinder ejects the paper tube and said plunger ejects the tobacco to form a completed cigarette.
